attorney.

UNITED STATES PATENT OFFICE.

WILLIAM HENRY HONSBURGER, OF WELLAND, ONTARIO, CANADA, ASSIGNOR OF ONE-FOURTH TO GEORGE C. BROWN, OF WELLAND, ONTARIO, CANADA.

ELECTRIC-LIGHTING APPARATUS FOR VEHICLES.

1,234,028.

Specification of Letters Patent. Patented July 17, 1917.

Application filed September 29, 1916. Serial No. 122,913.

To all whom it may concern:

Be it known that I, WILLIAM HENRY HONSBURGER, of the town of Welland, in the county of Welland and Province of Ontario, 5 Dominion of Canada, have invented certain new and useful Improvements in Electric-Lighting Apparatus for Vehicles; and I hereby declare that the following is a full, clear, and exact description of the same.

10 One of the principal causes of danger, in driving after dark, is the blinding effect of the glare from the head lights of an approaching vehicle, and to this numerous accidents are directly attributable. Various 15 devices have been provided to control this glare by limiting the diffusion of the light rays, and others have been provided for the dimming of the lamps. While most automobiles have been equipped with such devices 20 many drivers owing to the optical effects, resulting from the sudden change in the illumination, and the difficulty of seeing the road as a result of such change, fail, or neglect, to make use of the light controlling appliances, and the consequence is that approaching vehicles are in constant danger of accident until the glare has passed beyond the vision of the drivers.

My present invention, therefore, relates to 30 electric head lights connected in series or multiple to a source of current, and the primary object of the invention is to control the strength of these lights through the agency of an auxiliary light and resistor, 35 selectively cut into and out of circuit with the head lights by a set of switches which can be operated; (a) to close the circuit through the head lights and shunt it around the auxiliary light and the resistor whereby 40 the lamps of the head lights will be furnished with the maximum current for their greatest brilliancy; or (b) to place the resistor in circuit with the head lights and shunt the current around the auxiliary light, thus dimming the head lights without illuminating 45 the auxiliary light; or (c) to place the auxiliary light in circuit with the head lights, and shunt the current around the resistor, thus dimming the head lights and illuminating 50 the auxiliary light to its highest brilliancy; substantially as and for the purpose hereinafter set forth.

In the drawings:—

Figure 1, is a diagrammatic view showing 55 the head lights, and the auxiliary light and

the resistor connected in series, and Fig. 2, is a diagrammatic view showing the head lights, and the auxiliary light and the resistors connected in multiple series.

Like characters of reference refer to like 60 parts throughout the specification and drawings.

In Fig. 1, *a* represents the source of current, which in the case of automobiles usually consists of a motor generator or storage 65 battery; *b*, *b'*, represent the lamps, of the head lights *c*, *c'*, connected in series with the source of current *a* by the head light circuit comprising the conductors *d*, *d'*, *d''*, in which is the main switch *e*; *f* represents a 70 resistor and *f'*, *f''* the conductors of the resistor circuit, in which is a switch *g*, the conductor *d''*, being joined at *g'* to the conductor *f'*, *h* represents the lamp of the auxiliary light *h'* and *i*, *i'*, represent the conductors of the auxiliary light circuit, the conductor *i*, being joined at *i''*, to the conductor *f''*, and the conductor *i'*, returning to the source of current or ground; *j*, *j'* represent the conductors of a shunt circuit in which is a 75 switch *j''*, the conductor *j* being joined at *k*, to the conductor *i*, and the conductor *j'*, being joined at *k'*, to the conductor *i'*.

For the brilliant illumination of the head lights the switches *e*, *g*, and *j''* are all closed; 80 the circuit then being from the source of current *a*, conductor *d*, lamp *b*, conductor *d'*, lamp *b'* and conductors *d''*, *f'*, *f''*, *i*, *j*, *j'*, and *i'*, to ground or to source of current. 85 This arrangement of the switches while closing the circuit of the current through the head lights for their full illumination at the same time shunts the current around the resistor and the auxiliary light.

For the dimming of the head lights without the illumination of the auxiliary light, the switches *e* and *j''*, are closed, and the switch *g*, is opened, the circuit from the source *a* to the conductor *f'* being the same as that previously described and from the 90 conductor *f'* being through the resistor *f* to the conductors *f'*, *i*, *j*, *j'*, and *i'*, the resistance offered to the current in this circuit having the effect of reducing the strength of the light of the head lamps from 95 a glare to a glimmer, which is particularly advantageous in traveling through populous and well lighted localities, where the full strength of the head lights is not required, and the head lights can be dimmed, and as 100

auxiliary light can be provided to illuminate the road, by closing the switches e , and g , and opening the switch j'' , the circuit then being from the source a , through the conductors d , d' , d'' , f' , f'' , and i to the lamp h and return conductor i' , the current then being shunted around the resistor and through the lamp of the auxiliary light.

The lamp of the auxiliary light is of less candle power than the lamps of the head lights and draws the current from the latter and leaves them in a dimmed condition, the current then lighting the auxiliary lamp to its full brilliancy, for the illumination of the road, while the head lights remain so dimmed.

This auxiliary light is placed with respect to the vehicle so that it will clearly show the road to the driver of the vehicle with which it is used and at the same time will not project its light rays into the eyes of an approaching driver. As the traffic regulations in most places require approaching vehicles to pass to the left of each other, this auxiliary light may conveniently be placed at the right of the vehicle, preferably well back from the front, and if desired at an angle to the direction of travel to diffuse the light rays to the side instead of straight ahead, and clearly light the path which is to be followed.

In Fig. 2, y represents the source of current; x , x' , x'' , x^3 represent the head light circuit, and w , w' , the lamps for the head lights, v , v' , u , u' , represent the circuit for the resistor t , the conductor u' being joined at u to the conductors x'' , x^3 ; s , s' represent the auxiliary lamp circuit of which the conductor s is joined to the conductor u'' ; r , r' represent the conductors of the shunt circuit, of which the conductor r is joined to the conductor s and the conductor r' is joined to the conductor s' ; and z , z' , z'' represent the switches for the head light, resistor, and shunt circuits respectively.

When the head lights are to be brilliantly illuminated, the switches z , z' , z'' are closed, and the circuit of the current is from the source, y , of current, by means of the conductor x , to the conductor x' , lamps w , w' , of the head lights, v , v' , conductors x'' , x^3 , u , u'' , s , r , r' , and s' , but without going through either the resistor t or lamp s'' .

When the head lights are to be dimmed without illuminating the auxiliary light, the switches z , z'' , are closed and z' is opened,

the current from the circuit, x , x' , x'' , x^3 , then passing through the resistor t , to the conductors s , r , r' , s' , thus cutting out the auxiliary light.

When the head lights are to be dimmed and the auxiliary light illuminated the switches z , z' are closed, and the switch z'' is opened, the circuit then being by means of the conductors x , x' , x'' , x^3 , u' , u'' , and s , lamp s'' and conductor s' , to ground or source of current, the lamp of the auxiliary light being of less candle power than the lamps of the head lights, and the result being the same as in the system described with regard to Fig. 1.

By either of the systems above described the current may circuit through the head lights only, or the resistor may be connected in series with the head lights to reduce the strength of their illumination and the current shunted around the auxiliary light, or the auxiliary light may be connected in series with the head lights and the current shunted around the resistor for the brilliant illumination of the auxiliary light and the automatic dimming of the head lights.

Having thus fully described my invention what I claim as new and desire to secure by Letters Patent is:

An electric lighting apparatus for vehicles comprising, a switch controlled head light circuit, a switch controlled resistor circuit connected with the head light circuit, an auxiliary light circuit connected with the resistor circuit, and a switch controlled shunt circuit connected with the auxiliary light circuit, whereby the closing of the head light, resistor, and shunt circuits will cut out the resistor and auxiliary lights for the brilliant illumination of the head lights; and the opening of the resistor circuit and the closing of the head light and shunt circuits will place the resistor in series with the head lights for the dimming thereof without illuminating the auxiliary light; and the opening of the shunt circuit, and the closing of the head light and resistor circuits will cut out the resistor and place the auxiliary light in series with the head lights, for the brilliant illumination of the auxiliary light and the dimming of the head lights.

Welland, Ontario, September 16th, 1916. 110
